UNITED STATES PATENT OFFICE.

GEORGE N. PIFER, OF CLEVELAND, OHIO, ASSIGNOR, BY MESNE ASSIGNMENTS, TO F. E. STEWART, TRUSTEE, OF CLEVELAND, OHIO.

COIN-CONTROLLING MECHANISM FOR AUTOMATIC PHOTOGRAPHING-MACHINES.

1,229,515.

Specification of Letters Patent. Patented June 12, 1917.

Application filed April 16, 1913. Serial No. 761,447.

To all whom it may concern:

Be it known that I, GEORGE N. PIFER, a citizen of the United States, residing at Cleveland, in the county of Cuyahoga and

- 5 State of Ohio, have invented a certain new and useful Improvement in Coin-Controlling Mechanism for Automatic Photographing-Machines, of which the following is a full, clear, and exact description.
10 This invention relates to a coin controlling mechanism of an automatic photographing apparatus adapted particularly for use in connection with the photographing apparatus disclosed in my prior application Serial
15 No. 730,198, filed November 8th, 1912, of which the present application is in the nature of a division.

The main object of the present invention is to provide a coin controlling mechanism 20 which acting in conjunction with the coin causes the delivery of a sensitized plate to the camera, and at the same time operates a switch which may be a lamp and a motor controlling switch, together with means by 25 which the parts are restored to normal position, and the switch is opened after the picture is finished. A further object is to provide means by which the coin controlling mechanism is locked against movement or 30 operation while a plate is being operated on in the machine.

The invention may be briefly summarized as consisting in certain novel details of construction and combinations and arrangements of parts which will be described in the specification and set forth in the appended claims.

In the accompanying sheet of drawings, wherein I have shown an embodiment of my 40 invention which operates very satisfactorily, Figure 1 is a vertical sectional view through the apparatus; Fig. 2 is a horizontal sectional view with parts broken away, the section being taken substantially along the line 45 2-2 of Fig. 1, looking downward; Fig. 3 is a transverse vertical sectional view substantially along the line 3-3 of Fig. 1, looking in the direction indicated by the arrow; Fig. 4 is a similar view substantially along the 50 line 4-4 of Fig. 1; Fig. 5 is a detached view of the stationary plate on which part of the slide members operate; Figs. 6, 7 and 8 are respectively a side view, end view, and plan view of one of the slide members; Figs. 9 and 10 are respectively a side and plan view

of a second slide and switch operating member, and Fig. 11 is a diagrammatic view showing in simplified form, the electrical connections.

In the present application I have omitted 60 from the drawings, the major portion of the photographing apparatus, only such portions which are directly connected with the coin controlling parts being here shown, and for an understanding of the complete apparatus, reference is had to my prior application above referred to.

In the drawings, I have shown a camera which includes a lens holder 10, and a casing or camera box 11, the whole being inclosed 70 within a suitable cabinet, only the front glass plate 12 of which is here shown. Arranged above the camera box is a magazine 13, adapted to contain a quantity of sensitized plates P, which are used in the apparatus, these plates being preferably circular and being adapted to be placed in a stack, one upon the other, in the magazine.

The mechanism forming the subject matter of the present invention, when operated, 80 causes the delivery of a plate from the magazine to the focal plane of a camera, and operates a switch 14, which is used in the control of the apparatus. Preferably, this switch has a two-fold function of controlling a 85 lamp which supplies the light for the first and second exposures, the process which I use, being of the second or reexposure type, as described in my prior application, and the said switch may also be used in the control 90 of the motor, as hereinafter described.

Referring again to the drawings, it will be seen that there extends forwardly from the magazine, through an opening in the glass wall 12, a fixed slide support in the form of 95 a plate 15, a detail of which is shown in Fig. 5. This support 15 is secured to a projecting flange at the top of the camera box, see particularly Fig. 3. It will be observed that the plate 15 has along its side edges undercut slots which receive correspondingly shaped edges of an outer slide member 16, the details of which are shown in Figs. 6, 7 and 8. This slide member 16 has an 100 upstanding outer end 16^a, which is adapted to 105 be engaged by the operator when he desires to move the same inwardly to cause the coin controlling mechanism to start the operation of the apparatus. This slide member is provided also with a central longitudinally ex- 110

tending slot 16^b which is adapted to receive a second slide member 17, details of which are shown in Figs. 9 and 10. This slot 16^b is intersected between its ends by a circular opening, or otherwise stated, is provided with a circular enlargement designated 16^c, adapted to receive a coin 18, which forms the operative connection between the first and second slide members 16 and 17. At one part of the circular enlargement 16^c is a shoulder 16^d, for a purpose to be referred to presently.

The support 15 is provided with an elongated slot 15^b having between its ends a circular enlargement 15^c, and a shoulder 15^d, this slot, enlargement, and shoulder corresponding with the similar slot, enlargement and shoulder of the slide member 16. The slide member 17 is composed of two superimposed parts 17^a and 17^b, located in the slots 15^b and 16^b, the upper part 17^a having a pair of inwardly projecting fingers 17^c, through which extends a switch arm to be referred to presently.

25 The inner end of the slide member 17 is adapted to engage a third slide member 19 having a circular opening 19^a of a size just sufficient to receive one of the sensitized plates in the magazine 13. When the slide member 19 is in its normal and outermost position, this opening 19^a is directly beneath the circular magazine 13, so that the lowermost plate will occupy said opening.

When the three slide members above described, with the interposed coin, are moved inwardly, the said slide member 19 moves in the same direction the lowermost sensitized disk, and when the said disk is moved beyond a shelf or shoulder 20 at the top of 40 the camera box, the said plate tips and drops into a chute 21 and is stopped by a shoulder or platform 22 so as to stand edge-wise or in vertical position with the sensitized side facing forwardly in the focal plane of the lens, and directly in the rear of the lens holder 10. After the exposure has been made, the plate is caused to pass from the camera onto a horizontal support 23 during the developing operation, as is explained in my prior application.

As the middle slide member 17^a is moved inwardly, it causes the closure of the snap switch 14, which switch is provided with an operating arm 14^a, which extends between 55 the fingers 17^c, as before stated. As the arm 14^a is rocked by the slide mechanism, a spring 14^b, see Fig. 3, causes the movable contacts 14^c to be thrown with a snap action into engagement with the stationary contacts 14^d. At the same time, a locking pawl 24 is swung downwardly in front of the shoulders 16^d and 15^d of the outer slide member, and of the lower plate or slide support 15, and prevents the return of said slide members until after the picture is completed,

the locking pawl 24 being swung downwardly when the opening 16^c comes into registration with the corresponding opening 15^c and when the shoulder 16^d comes into registration with the shoulder 15^d. At this point, the coin 18 drops from the circular enlargement 16^c, of the slide member 16, through the circular enlargement 15^c, into a coin chute 25 which will direct the coin to a suitable receptacle, not shown.

When the slide mechanism is moved inwardly in the manner above stated, not only is the plate caused to be moved from the magazine to the camera, and is the switch closed, but a bell crank 26 at the rear of the magazine is rocked by the direct engagement of the rear end of the third slide member 19, with an upstanding arm of said bell crank. The second arm of the bell crank is connected by a rod 27 to a lever 28 located a short distance beneath the camera, and pivotally mounted between its ends upon a fixed rod 29. When the lever 28 is thus rocked by the slide mechanism and by the parts 26 and 27, one end of the lever is lowered to a position such that it will be in the path of movement of a lug 30, secured to the side of an operating disk 31 mounted on a motor driven shaft 32.

When the motor is started in operation, 95 this shaft 32 is driven, and after the completion of the several photographing and developing operations, the lug 30 again lifts the lever 28 to the position shown in Fig. 1. This rocks the bell crank 26 to the position 100 shown in Fig. 1, and this bell crank by moving the second and third slide members outwardly opens the switch 14 so as to stop the motor, elevates the locking pawl 24, and restores the parts of the slide mechanism to 105 normal position by moving the same forwardly. The parts are then in position for repetition of the operations above described.

By referring to the diagrammatic view of Fig. 11, it will be seen that when the switch 14 is closed by the slide mechanism, an electric lamp 33 is energized or lighted. This lamp is used when there is not sufficient natural light for the exposing process. The motor 34 is not yet started, as I propose to use in addition to the switch 14, a push button switch 35, which the operator will close when he is ready for the exposure to be made. As soon as this push button switch 35 is closed, the motor circuit is completed, 110 as will be seen by reference to Fig. 11, and as soon as the motor circuit is closed a magnet 36 is energized, which rocks an armature 37 and short circuits the switch 35. The motor continues to operate, and the 115 lamp continues to burn until the switch 14 is opened by the motor operated parts above referred to.

I have deemed it unnecessary to illustrate the motor, except in a diagrammatic man-

ner, for a complete illustration of the motor, and all the driven parts would introduce complications not necessary to an understanding of the present invention, these 5 parts being shown and described in my prior application.

In addition to the locking means above described which prevents the operation of the slide mechanism while one plate is being operated on by the photographing or finishing parts of the apparatus, I have provided also means for locking the slide mechanism or the main parts thereof against movement when the magazine is empty or when the 15 last sensitized plate previously in the magazine has been delivered to the camera. This locking means consists of a disk 40 which rests upon the uppermost disk of the stack in the magazine. This disk is of the same 20 diameter as the sensitized plates, but is somewhat thicker than the latter, so that when the plate just beneath the disk has been delivered from the magazine and when the parts of the slide mechanism have been 25 returned to normal position by the bell crank 26 and the parts operatively connected thereto, the said locking disk 40 drops into the circular opening 19^a of the slide member, 19 and thus locks the latter and the slide 30 member which is connected to the switch against inward movement. This, of course, prevents the switch 14 being operated and hence prevents the lamp being energized and the motor being started when the magazine 35 is empty.

Having thus described my invention, what I claim is:

1. A coin controlled mechanism for a machine having a magazine adapted to contain 40 articles said mechanism including a part which controls the delivery of articles from said magazine said mechanism also including parts adapted to be operatively connected by an interposed coin thereby when 45 actuated to cause the delivery of an article from the magazine, and a member adapted to engage one of the parts of the mechanism to positively move the said members to original position after they have been operated.
2. A coin controlled mechanism for a machine having a magazine adapted to contain articles said mechanism including a sliding part adapted to control the delivery of articles from the magazine, and a second sliding 55 part adapted to be connected with the first sliding part by an interposed coin, and means adapted to positively engage and move one of the sliding parts at the completion of predetermined functions.
3. A coin controlled mechanism for a machine having a magazine, an operating motor and motor controlling switch said mechanism including parts adapted to be operatively connected by an interposed coin and 65 when actuated serving to operate the switch

and to cause the delivery of an article from the magazine, and means engaging one of the aforesaid parts thereby to return the said part to its initial position and cause the opening of the switch.

4. A coin controlled mechanism for a machine having a magazine adapted to contain articles, a motor and motor controlling switch, said mechanism comprising slides adapted to be operatively connected by an 75 interposed coin and having a portion which causes delivery of an article from the magazine, and another portion operatively connected to the said switch, and means for positively engaging one of the said slides to return it to initial position and thereby cause the switch to be opened.

5. A coin controlled mechanism for a machine having a magazine, an operating motor and motor controlling switch said mechanism including parts adapted to be operatively connected by an interposed coin and when actuated serving to operate the switch and to cause the delivery of an article from the magazine, means for locking one of the 90 said parts when the said parts have been operated, and means for positively engaging one of said parts to move the same to initial position and also moving the switch to original position and causing the locking means 95 to release.

6. A coin controlled mechanism for a machine having a magazine adapted to contain articles said mechanism including a sliding part which controls the delivery of 100 articles from the magazine, and a second sliding part co-operating with the first sliding part and adapted to be operatively connected thereto by an interposed coin, a support for the second sliding part said support having 105 an opening provided with a shoulder the second mentioned sliding part also having a shoulder which registers with the first mentioned shoulder when the slides are operated, a latch operated by the movement 110 of the slide adapted to engage the said shoulders to hold the second slide member in locked position, and means for causing the release of said locking member.

7. A coin controlled mechanism for a machine having a magazine, an operating electric motor and a motor controlling switch, said mechanism including a sliding part adapted to control the passage of articles from the magazine, and having a portion 120 which operatively engages said switch, a second sliding part adapted to be connected with the first sliding part by an interposed coin, means operatively engaging the second slide to return it to initial position 125 thereby simultaneously opening the switch.

8. A coin controlled mechanism for a machine having a magazine from which articles are adapted to be delivered, comprising a pair of movable members adapted to be 130

1
operatively connected by an interposed coin, and serving when moved in one direction to cause the delivery of an article from the magazine, and locking means operated by 5 the movement of said mechanism in one direction for preventing movement of one of said members in the reverse direction until the completion of predetermined functions whereby the insertion of a coin into the 10 mechanism is prevented until the locked member is released.

9. In a coin controlled mechanism, a slide composed of two relatively movable members, one having an opening to receive a 15 coin and the other adapted to be operatively connected to the first by the interposed coin, a locking device adapted to lock the first member when said members and the coin are moved in one direction, said locking device being operated by the second member.

10. A coin controlled mechanism for a machine having a magazine from which articles are to be delivered, comprising two members adapted to be connected by an 20 interposed coin and serving when moved inwardly to cause the delivery of an article

from the magazine a locking device for temporarily locking one member against outward movement whereby the insertion of a coin into the mechanism is prevented until the locked member is released, and means for unlocking the locked member. 30

11. A coin controlled mechanism for a machine having a magazine from which articles are to be delivered, said mechanism including an outer slide adapted to be manually pushed and to receive a coin and an inner slide adapted to be connected to the first by the coin, a locking device for locking the outer slide when it is moved manually in one direction to cause an article to be delivered from the magazine, and means for subsequently actuating said locking device to release said outer member and for positively moving the inner slide to normal 40 45 position.

In testimony whereof, I hereunto affix my signature in the presence of two witnesses.

GEORGE N. PIFER.
